COUNTER

Adolf Holzner, Brooklyn, N. Y.

Application September 25, 1933, Serial No. 690,811

1 Claim. (Cl. 235—117)

The purpose of this invention is to provide in a device including a total and a separate score counter having their operating means in common, and including a resetting mechanism of the 5 separate score counter to zero without disturbing the score in the total score counter, and vice versa, a means for operating the total score counter alone for subtraction, while the separate score counter remains stationary.

10 With these ends in view, my invention relates to counters as they are for instance described in my patent application Serial No. 554,475 filed August 1, 1931 and in my co-pending patent application Serial No. 142,975 filed May 17, 1937, 15 of which I desire hereby to give notice, and which is a continuation in part of my present application.

It is the object of the present invention to provide a combination of oppositely disposed 20 counters in which the shaft requiring means for returning the number wheels of one counter into their zero position, is simultaneously also used for the operation of the number wheels of the oppositely disposed counter, while the mechanism 25 for the returning of the number wheels into their zero position is arranged on the outside of all number wheels.

It is the general object of my invention to arrange two oppositely disposed counters for two 30 players, whereby each player will be able to keep score in a total and a separate score counter with operating means in common, and whereby the two total and the two separate score counters can be reset to zero independently of one 35 other. It is well known that by the operation of a total and separate score counter a score will be set in both counters, and the separate score counter must allow the resetting of the score displayed in said counter without disturbing the 40 total score.

It is, however, the principal purpose of this invention to provide a means so that the total score counter alone can be operated for subtraction while the separate score counter remains stationary and the resetting of the separate score counter can be effected without disturbance for the score in the total score counter.

It will be understood that the counter by the 50 co-operation of the individual mechanisms can conveniently be used for keeping score in a pocket-billiard game, as it facilitates the score keeping of the total and separate score because it does away with the difficulties inherent to the 55 subtraction operation of a ball in default from

the total score by means of rings suspended from a wire which often creates confusion among the players.

If desired, the counter can be countersunk in the billiard table, or preferably be placed upon a post or stand or hung to a wall, to allow a perfect survey of the game, as it creates great interest in the game with the players as well as with the onlookers because they will be able to ascertain at one glance the state and progress of the game, as instantaneously a comparison can be made between the status of the first and second player by momentarily inspecting their total scores.

By the arrangement of a left hand and the right hand counters in one casing adapted to be operated by a common centrally located toothed disc, the right hand counters could for instance be used to keep the score made in one day and which can be returned to zero at the close of the day, while the left hand counter is used to count the sum of scores made on the individual days of an entire week.

In the accompanying drawings forming a material part of this disclosure:

Fig. 1 illustrates in front elevation a counter constructed according to my invention after removal of its cover plate and in the zero position of the counting or numeral wheels (i. e. before the start of the counting operation).

Fig. 1a illustrates the operation of the counter mechanism of Figure 1 during the setting back position of the numeral wheels to zero position.

Fig. 2 is an end view of the counter seen in the direction of arrow 2 of Figure 1.

Fig. 2a is a view similar to Figure 2 seen in the direction of arrow 2a of Figure 1a.

Fig. 3 is a view similar to Figure 2 seen in the direction of arrow 3 of Figure 1.

Fig. 3a is a view similar to Figure 2a seen in the direction of arrow 3a of Figure 1a.

Fig. 4 is a view similar to Figure 2 seen in the direction of arrow 4 of Figure 1.

Fig. 4a is a view similar to Figure 2a seen in the direction of arrow 4a of Figure 1a.

Fig. 5 illustrates in sectional detail view the mounting and arrangement of the number wheels upon their shaft.

Fig. 6 is a cross section in the direction of arrow 6, Figure 5.

Fig. 7 illustrates a counter constructed according to my invention in front elevation adapted to be countersunk into a depression of a billiard table.

Fig. 8 is an end view thereof seen in the direction of arrow 8 of Figure 7.

Fig. 9 is a cross-section seen in the direction of arrow 9 of Figure 7.

5 As illustrated for the better understanding of my invention the parts of my counter are designated as follows:

The transmission shafts are designated c and c^2 and carry respectively the wheels 22 (having 6 10 teeth) and the bushings 23 which are arranged between each two gears in order to keep distance between wheels 22.

The slides are designated 9, 10, 11 and 12 and the springs 1, 2, 3 and 4.

15 The shaft carrying the cams and the gap gears is designated A and the gap gears on this shaft returning the parts to zero position are designated 16 and have as shown in Figure 3, six teeth and two gaps at opposite points. The 20 gap wheels on the shafts B and B_2 belonging to the number wheels are designated 21 and have 9 teeth and one gap.

As shown in Figures 1, 2, and 2a, the rotation of shaft A will press cams 17 and 18 upon the 25 slides, cam 17 upon slides 9 and 10 (Fig. 1) and cam 18 upon slides 11 and 12 (Figs. 2 and 2a).

By these operations the slides will displace the shafts c and c^2 (Fig. 4a) upon which the gears 22 are loosely arranged and uncouple there- 30 by all gears 19 at the number wheels, as the slides are mounted at the ends to spindles or shafts c , c^2 .

In order to enable this displacement, the slides have each a longitudinal slot 26, the slots within 35 the casing for the shaft c are designated 5 and 8 and for the shaft c^2 , 6 and 7 respectively.

40 Springs 1, 2, 3 and 4 serve the purpose to return the slides into their notches, in the cams. Cam 18 has two notches 18a and 18b (Fig. 2) and cam 17 has also two notches.

As shown in the sectional views in Figures 2, 3 and 4, taken on lines 2-2, 3-3 and 4-4 on Figure 1 respectively, the number drums or wheels are in their zero position in which the 45 gaps of gears 21b are in a position exactly in alignment with the center portion of shaft A. If, however, the number wheels are turned in either direction from the zero position to display any other number than zero, the gaps of 50 gears 21b will also take up another position relatively to shaft A and a tooth of said gears will now be oppositely disposed to the gaps in wheel 16.

If now shaft A is rotated, the teeth of gear 55 16, will mesh with the respective tooth of gears 21b.

In order to bring gears 21b to a position in which their number wheels show a number which is as far as possible remote from zero, it will be 60 necessary to impart to gear 16 one and a half rotations, consequently it will be apparent that if the number drum is turned to a number next to zero, gears 21b will rotate the same to zero within an adequate revolution of shaft A.

65 During the rotation of the number wheels to zero, gears 19 will participate in their rotation, until shaft A and gear 16 take up the position shown in Figure 3a. The teeth of gears 19 are so arranged as to be in alignment with the inter- 70 stices between the teeth of gears 21b, consequently at any movement of gears 21b bringing one of their teeth in alignment with the center line of the shafts, an interstice of gear 19 will also be in alignment with the center line of the 75 shafts, and consequently when an interstice of

gear 21b is in line with the shaft, a tooth of gear 19 will also be in this alignment.

Figure 3 shows gears 21b zeroized, and it will be clear that in any other position of the number wheels of the counter showing or displaying any other number than 0, the gaps 25 of gear 21b will have assumed different positions than that shown in Figure 3, as for instance shown in Figure 3a and one tooth of gear 21b will appear in alignment with the center line of the shaft A. 10 Consequently if now the shaft A (Fig. 3) is turned for an adequate amount, preferably 30°, it will bring one tooth of gear 16 in engagement with one tooth of the gear 21b. The cams 17, 18 are so selected that they displace the slides 15 during the rotation of the shaft A for 30° so far that the gears 22 on shafts c and c^2 which are located within the slides, are disengaged from the gear 19 during this time and no jamming in the machine will be caused. It will further be clear that a gear having a number of teeth not divisible by four cannot, if one gap of gear 19 is in alignment with the center line of the shafts, after an adequate revolution, for instance a quarter revolution, again engage a 25 gap of gear 19 but will engage one tooth, as shown in Figure 4a.

This is not the case after the shaft A has made one half revolution as then the cams 18 have turned to assume the position shown in Figure 2 and the wheels 19 assume the position in Figure 4 and can be coupled.

The springs R engaging the gap wheels 21, two springs for each gap wheel, (Figs. 3 and 3a) serve the purpose of preserving the alignment 35 in order to keep the numbers on the number wheels in a perfect row.

While these springs are shown only in Figures 3 and 3a, it is clear that they are also present in the counters shown in Figures 1 and 1a 40 and are omitted from the drawings only for the sake of clearness.

When the shaft A is turned from its normal position in Figure 2 to the position of Figure 2a, and the cams 17 and 18 move the slides 9, 10, 11 45 and 12, the gears 16 will then mesh with the gears 21, of which each numeral wheel has one (Figs. 3, 3a).

The gears 16 mesh with gears 21 until the 50 gaps 25 of every gear 21 come into alignment when no further rotation of wheels 21 will take place (Fig. 3) and the number wheels arrive at zero position after one and one-half revolutions of the shaft A from the position farthest possible from zero.

In order to space the wheels 21 on shafts B and B_2 from the wheels 16 so that they may pass the same (during the counting operation) from both halves of the wheels 16 teeth are removed to create gaps 16a, 16b.

Figures 5 and 6 illustrate the arrangement of the number wheels upon the shaft or spindle B_2 each number wheel having a bushing telescoping into the adjoining bushing, while number wheel b is secured to spindle B_2 , and then the 65 number wheel c with its bushing is loosely brought upon shaft B_2 , whereupon the number wheel d with its bushing is brought upon the bushing of wheel c and then number wheel e is brought upon bushing of number wheel d . Number wheel e carries on its left hand end the gap gear 21e. All gap gears 21 are secured to the ends of the bushings and the gear 21b is secured to the number wheel shaft B_2 which belongs to number wheel b .

The number wheel *a* is secured to bushing 24 together with gear 21*a*, and the bushing is loosely brought upon the shaft B₂. The operating knob 14 is secured to bushing 24 at the 5 outer end of the casing.

Figure 4 shows the counter during the counting operation, and Figure 4*a* shows the counter during the zero resetting operation.

Each number wheel is equipped with a wheel 20 having one tooth, with the exception of the last number wheel *e*. In the same way each number wheel is also equipped with a wheel 19 having ten teeth, with the exception of the first number wheel *a*.

If the number wheel *a* is turned in the direction in which the numeral 1 follows upon 0, the single tooth on wheel 20 is disengaged from wheel 22. If now the turning of the number wheel *a* is continued, until the numeral 9 appears, the single tooth of wheel 20 will in this moment assume a position in front of a tooth of wheel 22. If now the turning of the number wheel *a* is proceeded with, so that the 0 appears on wheel *a* and on number wheel *b* appears the number 1 thus the counter shows number 10.

This result is obtained because the tooth of wheel 20 is coupled with the wheel 22 and because wheel 22 is coupled to wheel 19 of the number wheel *b* the latter must also turn, and in this manner the transmission from one number wheel to the other is effected.

It will be understood that I do not wish to limit myself to the specific construction shown and described, and that I may arrange the gap wheels and the cams in a counter within its casing in any suitable manner coming within the scope of the appended claim.

I may thus for instance use gap wheels having gaps at both of their halves and cams having notches at both of their halves, which I for instance use if a plurality of counters is used in one casing. With such construction I obtain the advantage of requiring 1½ revolutions only in order to return the number wheels into their zero position.

In Figures 7 to 9 I have shown a special construction of counter adapted to be countersunk into a depression of a pool table to keep a convenient count of the score of two pool players the 50 counting mechanism of which is substantially the same as described above, the difference residing in the manner of coupling the same.

The housing of the counting mechanism according to this form of my invention is attached to a bi-partite front plate 51, 52 which carries at its front a console or bracket 50 presenting a depression through which the wheel 43 projects with its teeth allowing the start of the counting operation by pressing one of its teeth downwards. Plates 51, 52 are wider than the casing for the counter as shown in Figures 8 and 9 so as to support the same as at 53 when the housing is countersunk into the depression of the pool table, and 64 designates the base plate of the counter, and this plate 54 appears in the space between plates 51, 52.

In Figure 7, counters B and B₂ and their mechanism are the same as illustrated in Figures 1 to 6.

This is good also for counters B₅ and B₆ having however three number wheels only and the first number wheel *a* is secured to the shaft as for instance number wheel *b*, Figure 5.

The left hand upper counter B is coupled with 75 the right hand counter B₆ and the left hand lower

counter B₂ is coupled with the right hand counter B₅.

The bushing 24 upon the shaft of counter B₂ with which the counting operation starts, the same as in Figure 1, is secured to a wheel 37. 5 This wheel 37 has ten inclined teeth 42, and so has wheel 38 on the shaft of counter B₅ and both wheels are coupled, so that upon starting the counting operation by the downward rotation of wheel 43 attached to wheel 37, bushing 24 on the 10 shaft of counter B₂, and the shaft counter B₅ will be rotated to operate both counters.

If however the wheel 43 is rotated in the opposite direction or towards above in counter B₂ a subtraction is effected, while counter B₅ will remain at rest. The explanation for these operations is as follows:

During the upwardly directed rotation of wheel 43 the wheel 37 will thrust off wheel 38. This is possible because coupling member 37 is secured to the bushing 24 of the left hand counter B₂, and coupling member 38 is displaceable in the direction of the longitudinal axis of shaft of counter B₅. Coupling member 38 is provided with a groove 39 engaged by a pin 40 secured to shaft of counter B₅, while a spring 41 pressed against coupling member 38 so as to couple members 37 and 38 during the counting operation while they are separated during the subtraction operation.

A ratchet 45 and its spring 49 at the end of the 30 shaft of counter B₅ permits the rotation thereof in one direction only (towards below), so that during the rotation of wheel 43 in upward direction, the wheel 38 is thrust off by wheel 37 for one tooth and the spring 41 will return wheel 38 into 35 engagement with wheel 37 and both wheels are coupled.

Wheel 37 upon its downwardly directed rotation takes along wheel 38. Upon the upwardly directed rotation of wheel 37 it will thrust off 40 wheel 38 as ratchet 45 does not permit a rotation of shaft B₅, the same will remain idle while during each thrust off movement of wheel 38 the same will slide along on pin 40 in groove 39.

The plates of the counter are secured to the 45 pool table into a depression of which the entire mechanism is countersunk, by means of the screws 55, and it will be necessary to provide a mechanism for returning the counter into zero position outside of the counter, and for this purpose I provide the depression 58 (Fig. 7). Into 50 this depression projects the end of the zero shaft A and carries there a bevel gear 46 having 6 teeth, which meshes with a bevel gear 47 (with 12 teeth, of which three teeth are broken away, as indicated at 47*a*) having thus 9 teeth.

The bevel gear 47 is secured to a shaft 48 extending through the housing to the outside and is provided with a square boss for engagement by a suitable key for its operation.

If now the bevel gear 47 is rotated once, both 60 counters B₅ and B₆ are returned to zero position, as the bevel gear 46 on shaft A must execute one and one-half rotations to return the parts into zero position, this will be effected during 65 one rotation of the bevel gear 47 as the gear 46 has 6 and the gear 47 nine teeth.

The rotation is effected as far as it is permitted by the ratchet gears 45. Gear 47 must be turned 70 towards the left and the shaft A will be turned towards the right, and both shafts of the counters B₅, B₆ are rotating towards the left and wheel 38 is thrust off from wheel 37, and spring 44 will prevent the wheel 43 from turning and thus during the turning of the two right hand 75

counters B_5 , B_6 no operation of the two left hand counters B_1 , B_2 will be effected, which count the total of the score of both players. It will be clear that care must be taken to submit spring 5 41 to a pressure just sufficient to permit coupling member 37 to take along coupling member 38.

Therefore the strength of spring 44 must be so selected as to develop twice as much force of 10 resistance as spring 41 in order to prevent the operation of the two left hand counters during the turning of the two right hand counters B_5 and B_6 into the zero position when coupling member 38 thrusts off member 37 and spring 15 44 which has the same size as the width of wheel 43 prevents the rotation of the same.

Therefore, if it is desired that during the returning of the two left hand counters into the zero position no operation of the two right hand 20 counters be effected, the shaft A (Fig. 1) must be so rotated that the wheels 37 thrust off the wheels 38, which means that the shaft A in counter B_1 , B_2 (Fig. 1) must be turned towards below, as indicated in Figure 7, however shaft A in counters B_5 , B_6 (Figs. 7, 8) must be turned towards above.

In order to make the operation of my counter clear, I will herebelow explain by examples the 30 method of operating the same in practice.

If for instance two players agree to play a game for a total score of 50 balls, the upper left hand counter B counts the total sum of the balls detailed to one of the players while the lower counter B_2 those for the other player.

Both counters B and B_2 are only once returning to zero position i. e. after the game is finished and a new game starts.

However the two right hand counters are often returned to zero position during the play 40 (after all balls upon the pool table have been shot).

The player whose score is counted by the upper two counters is designated the first and the 45 player whose score is counted by the lower two counters is designated the second.

Assumed, the first player at the start of the game shoots three-balls off the table and while shooting at the fourth, predetermined ball, he 50 hits the ball, but does not shoot the ball into the predetermined pocket of the table, so that now the second player starts his play.

The first player will now count his balls by the 55 operation of wheel 43 by turning the same for three teeth towards below so that in the left hand counter B and in the right hand counter B_5 the following numbers appear: B 00003— B_5 003.

If now the second player shoots 8 balls off the 60 table, and while shooting at the ninth ball, he hits the predetermined ball, but his white or play-ball runs into one of the pockets of the table a ball must be subtracted from his total in the left hand counter B_2 , and the player 65 counts the balls he made by the operation of the lower wheel 43 turning this wheel eight times towards below, so that in the right hand counter B_5 and in the left hand counter B_2 the number 8 appears and the counters will show the following 70 results:

B 00003— B_5 003— B_2 00008— B_5 008.

This player however must now deduct one ball by turning the wheel 43 one step upwardly and 75 thus the left hand counter B_2 will show 7 and

the right hand counter 8. Thus: B 00003— B_5 003— B_2 00007— B_5 008.

Now the first player will start playing again, and for instance shoots three balls so that only one other ball remains upon the table to be shot 5 at besides the white ball.

It is the rule of this game that 15 balls are placed upon the table and are all to be played off with the exception of one single ball. This ball remains in its place and the other balls 10 which have been shot at are placed again upon the table in a triangular frame.

The first player now counts his three balls by means of the upper wheel 43 and in the left hand counter B and in the right hand counter 15 B_5 the number 6 will appear, thus B 0006— B_5 006 B_2 0007— B_5 008.

If now all balls have been shot from the table except the remaining single ball, the two right hand counters B_5 and B_6 are returned to zero 20 position and the counters will indicate the following: B 0006— B_6 000— B_2 00007— B_5 000.

The first player is now entitled to proceed with shooting upon the newly aligned balls, he shoots 25 seven balls off the table and while shooting at the eighth ball he misses the predetermined ball, which requires a subtraction from his total, so that he must now count seven balls only by turning the wheel 43 seven times towards below and then turns the wheel 43 once towards above. 30 Thus the left hand counter B shows the number 13 and the right hand counter B_6 the number 7, thus: B 00013— B_6 007— B_2 0007— B_5 000.

If now the wheel 43 is turned towards above, 35 the left hand counter B will display the number 12 and the right hand counter B_6 the number 7, thus: B 0012— B_6 007— B_2 00007— B_5 000.

The second player now shoots four balls off the 40 table and misses the next one, this player must therefore turn the wheel 43 four times towards below and in the left hand counter B_2 the number 11 will appear and in the right hand counter B_5 the number 4, thus: B 00012— B_5 007— B_2 00011— B_6 004 and the play is now 45 continued until in one counter of the two left hand counters B , B_2 the number 50 appears and this player will have then won the game.

It will be understood that I have described and shown the preferred forms of my counters as some examples only of the many possible ways to practically construct my invention, and that I may make such changes in the general arrangement of the counters, and the construction of their minor details as come within the scope of 50 the appended claim without departure from the spirit of my invention and the principles involved.

Having thus described my invention, what I 55 claim as new and desire to secure by Letters Patent is:

In a mechanism as described, including, a "total score" counter, and a "separate score" counter, an operating wheel between the two counters to be rotated in one direction for adding the score in both counters, a coupling in said 65 operating wheel, composed of two members, the first coupling member secured to said operating wheel and firmly and operatively connected to the "total score" counter, and the second coupling member grooved and displaceable in longitudinal direction upon the spindle of the "separate score" counter, a pin secured to said spindle, the grooved member of the second coupling member guided on said pin, a ratchet wheel upon the spindle of the second coupling member to permit 70 75

the rotation of said spindle in one direction only, and a coil spring upon the second coupling member to return both coupling members into their coupling position after each separation of said coupling member by the operation of said operating wheel to subtract in the counter of the total

score by rotating the operating wheel in a direction opposite to its direction of rotation for adding the score, the separate score counter then remaining stationary.

ADOLF HOLZNER. 5
